Hawson & Hawson

UNITED STATES PATENT OFFICE

HENRY K. HARWICK, OF DARBY, PENNSYLVANIA

LOCOMOTIVE CENTER PLATE

Application filed April 2, 1929. Serial No. 351,947.

My invention relates to certain improvements in securing a center bearing to an integral frame of a locomotive.

One object of the invention is to so design the center bearing structure that it will rest against the upper web of the main frame which is reinforced by the cylinder structure when said cylinder structure is directly above the center bearing.

Another object of the invention is to so design the main frame that the center bearing and cylinder structure can be readily secured to the main frame without recourse to difficult structural features.

In the accompanying drawings:

Fig. 1 is a cross-sectional view of the main frame of a locomotive made in accordance with my invention, showing the cylinder structure and the center bearing in position;

Fig. 2 is a sectional plan view, on the line 2—2, Fig. 1, of that portion of the engine frame to which the center bearing plate is attached;

Fig. 3 is a transverse sectional view on the line 3—3, Fig. 2;

Fig. 4 is a sectional view illustrating a modification of the invention; and

Fig. 5 is a view showing my invention applied to a locomotive having side frames and a connecting bed frame.

Referring to the drawings, 1 is the main frame of a locomotive, in the present instance being an integral casting, which extends the full length of the locomotive, but the frame may be made in sections without departing from the main features of the invention.

2 is the cylinder structure which is shown frame of a locomotive, in the present instance but it will be understood that it may be made in two parts bolted together in the ordinary manner if desired. In the cylinder structure 2 are the cylinders 3 and valve chests 4, and 5 is a saddle on which the boiler rests.

Extending from one cylinder to the other is a horizontal web 5^a, depending from which are the vertical flanges 6. The cylinder structure fits over the frame 1 as clearly shown in Fig. 1, and is secured thereto by bolts 7 which pass through the vertical side mem-

bers 8 of the frame 1 and through the flanges 6 of the cylinder structure.

The bottom of the frame has a web 9 which projects from the lower end of the side members 8 of the frame, leaving an opening 10 through which the bolts 7 are passed when the parts are assembled and secured together.

Projecting from each web 9 are lugs 11, and from the cross-members 12, which are a continuation of the webs 9, extend lugs 13.

The center bearing plate 14 of the center bearing 16 is made as shown in Fig. 2, and is extended so as to pass under the lugs 11 and 13 in the present instance, and vertical bolts 15 secure the center bearing plate to the lugs, as clearly shown in the drawings.

The center bearing structure 16 extends into the locomotive frame and the upper portion 17 of the structure bears against the underside of the upper web of the main frame, which in turn is in contact with the cylinder structure, making a very substantial support for the center bearing structure. The interior of the center bearing structure is preferably provided with vertical reinforcing ribs 25,

and on the outside are reinforcing ribs 18. Secured to the lower portion of said bearing structure is a wear plate 19 which is secured to the center bearing structure by vertical bolts 20.

21 is the upper portion of a truck center bearing forming part of the bolster of the truck. This truck center bearing has a flange 22 within which is located the engine frame center bearing disk 19, and between these two bearings are liners 23 of the usual type. A king bolt 24 is shown by dotted lines in Fig. 3.

In Fig. 4 I have shown the locomotive frame 1^a having upturned lugs 11^a, and the center structure 16^a is also provided with upturned flanges 26, and transverse bolts extend through openings in the two flanges and secure the center bearing structure to the main frame. In this figure the center bearing casting is extended at 19^a to form an integral wear plate. Preferably surrounding this depending portion 19^a is a wear collar 27 which is shrunk upon or welded to said portion.

By making the main frame, the cylinder

structure and the center bearing structure in the manner shown, a very firm support is provided for the center bearing structure, and the load on the engine truck is transmitted directly from the cylinders through the upper web of the frame to the center bearing structure and to the bolster, making a very substantial arrangement of parts.

In Fig. 5 a modification is illustrated, in which ordinary longitudinal side frames 1^a are used to which the cylinder structure 2^a and the connecting bed frame 1^b are secured by bolts 7^a. The center bearing structure 16^b extends into the bed frame 1^b and rests against the underside of the upper web 17^a, which is reinforced by the cylinder saddles. In this figure the saddle is shown as a two-part saddle. The flanged side portions 28 of the center bearing fit neatly in the bed frame 1^b as shown, and upright lugs 29 are bolted at each end to the bed frame.

I claim:

1. The combination of a locomotive frame having an upper web; a cylinder saddle mounted thereon; and a center bearing structure extending into the frame and resting against the upper web of said frame.

2. The combination of an integral locomotive frame having side members and an upper web; a center bearing structure mounted within the frame and resting against the underside of the web; and means for securing the center bearing structure to the frame.

3. The combination of a locomotive frame having upper and lower webs; and a center bearing structure extending into the frame and resting against the upper web and having a plate secured to the lower webs.

4. The combination of an integral locomotive frame having side members; an upper web and inwardly extending lower webs; a cylinder saddle mounted on the frame and having depending flanges fitting the sides of the locomotive frame; transverse bolts extending through the sides of the frame and through the flanges of the cylinder structure, the frame being open on its underside so that access may be had to said bolts; and a center bearing structure mounted within the frame, and resting against the upper web thereof and secured to the lower portion of said frame.

5. The combination of an integral locomotive frame having side members; an upper web extending from one side to the other; webs projecting inwardly of the lower portion of the side members of the frame; a center bearing structure having a cylindrical central portion extending into the frame and resting against the upper web; and a plate at the lower portion of the center bearing structure, and having projections secured to the lower inwardly projecting webs of the frame.

6. The combination of an integral frame

having side members and upper and lower webs; a large opening in the lower web; lugs projecting from the edges of the web into the opening; a center bearing structure having a cylindrical body portion extending into the frame and resting against the underside of the upper web; a reinforced plate at the lower edge underlapping the lugs; and vertical bolts securing the plate to the lugs.

7. The combination of a locomotive frame having side members and an integral upper web and an integral lower web; a center bearing structure mounted in the frame and resting against the underside of the upper web; a plate secured to the lower web; a wear plate secured to the underside of the center bearing; and means for securing the wear plate to the center bearing structure.

8. The combination in a locomotive, of a frame having an upper web; a cylinder saddle extending over the frame; and a center bearing structure extending into the frame and bearing against the upper web of said frame, said center bearing structure being secured to the frame.

9. The combination in a locomotive, of a frame having an upper web; and a center bearing structure fitting the frame, the upper end of the structure resting against the web of the frame.
